MICROWAVE WAVE ELECTRONIC
DISCHARGE DEVICEJohn R. Harbeck, IBMBETON, N. J., assignor to Bell
Telephone Laboratories, Incorporated, New
York, N. Y., a corporation of New York

Application January 11, 1946, Serial No. 600,650

12 Claims. (Cl. 315--5)

This invention relates to electron discharge devices and more particularly to such devices where an energy interchange is effected between an electron beam and electromagnetic waves in a region traversed by the beam.

An object of the invention is to provide high gain, broad band amplification of electromagnetic waves, particularly in the microwave range.

A related object is to provide a substantially flat gain frequency transmission characteristic over a broad band of frequencies.

An amplifier employing a pure traveling wave is to be preferred, especially in applications where it is desired to amplify complex electromagnetic waves having frequency components extending over a wide frequency band. By a pure traveling wave is meant a wave which progresses continually in a single direction without reflection. Where reflection and the resulting standing waves occur, the intensities of the electric and magnetic forces vary from point to point and the manner of their variation depends upon the frequency of each wave component involved. Such intensity variations, in an amplifier, result in a variable amplification factor which is a function of the frequency, that is, the gain frequency transmission characteristic is not flat. With a pure traveling wave on the other hand the absence of standing waves eliminates this source of frequency variation of the amplification factor. Accordingly, an electron beam amplifier acting upon a pure traveling wave in a suitable transmission line structure or other transmission medium is inherently capable of uniform or flat transmission over a broader frequency range than may be had with an amplifier acting upon standing waves.

More specifically the device is of the type in which there is designed to be substantial equality between the speed of the electrons in the electron beam and the speed of propagation of the electromagnetic waves in the direction of progression of the beam.

The advantage of a substantial equality of the speeds lies in the fact that the phase relationship between an electron and the wave will remain substantially unchanged over a considerable time interval. Thus, an electron which is in the proper phase relationship to the wave to receive energy therefrom will continue to receive such energy as long as the speeds remain substantially equal. The electron will gain speed continuously until the increase in its speed results in the electron progressing into a region where the phase relationship is reversed. Similarly, an electron

which is in the proper phase relationship to the wave to contribute energy thereto will continue to do so for a time. Bunching of the electrons will result when electrons that have been accelerated by receipt of energy from the wave overtake electrons that have been decelerated by loss of energy to the wave. A group of electrons moving together at substantially the speed of propagation of the wave, when once in the proper phase relationship to the wave to deliver energy thereto will do so continuously over an extended interval of time, similarly as in the case of a single electron.

A feature of the invention is a means for adjusting the speed of propagation of an electromagnetic wave in a wave guide structure.

A number of embodiments of my invention are described in detail hereinafter while the scope of the invention is defined in the appended claims.

In the drawing,

20 Fig. 1 is a longitudinal sectional view of one embodiment of the invention shown partly in perspective and partly diagrammatically;

25 Fig. 2 is the same kind of a view of another embodiment of the invention;

30 Fig. 3 is a fragmentary longitudinal sectional view in perspective of a structure of the kind shown in either Fig. 1 or Fig. 2; and

35 Figs. 4 and 5 show respectively a representative disc and ring from which may be assembled a structure similar to that shown in Fig. 3.

Referring to Fig. 1, there is shown a hollow pipe wave guide 10 containing a series of transverse baffle plates 11, each plate having a centrally located aperture which may be circular. The wave guide 10 has end plates 12 and 13, respectively, which also have centrally located apertures. A toroidal resonator 14 with a centrally located aperture in one portion thereof is arranged in proximity to the wave guide 10 and separated therefrom by a constricted intermediate section 15 of hollow pipe wave guide. In proximity to the end plate 12 there is mounted a cathode 16 enclosing a heater 18 and having an active face 19 opposite the aperture in the plate 12. The face 19, the apertures in the plates 11, 12 and 13, the central axis of the constricted intermediate section 15 and the aperture in the toroidal resonator 14 are all in alignment with each other. An insulating vacuum tight dome 20, which may be of glass, is sealed to the end of the wave guide 10 over the end plate 12 and has a tip or press 21 through which the necessary leads for the heater and the cathode are brought out. A lead 22 connected to the cathode and one side of the heater 18 goes to the negative terminal of a battery 23 which

serves as an anode potential supply source, the positive terminal of the battery being connected through a lead 23 to the wave guide structure. The potential of the battery 22 is preferably adjustable. The wave guide, plates 11, 12 and 13, the resonator 14 and the constricted intermediate section 15 are all of metal of high conductivity or have highly conductive surfaces where exposed within the vacuum tight system. All the metal parts exclusive of the cathode and heater are connected together in good electrical contact and the whole structure is made vacuum tight.

As the means of insuring a substantially pure traveling wave in the interior of the metallic structure, a resistor 24 is provided between the end plate 13 and the nearest baffle plate 11. The resistor 24 is preferably in the form of a post, rod, wire or other like structure and is composed of material of relatively high resistivity.

An input coaxial line is provided having an inner conductor 25, an outer conductor 26, the inner conductor 25 terminating in a coupling loop 27 which enters an opening in the pipe 10 through an insulating and sealing bushing 28. An output coaxial line is provided having an inner conductor 29 and an outer conductor 30, with the inner conductor terminating in a coupling loop 31 inside the resonator 14, entering through an insulating and sealing bushing 32. The outer conductors 26 and 30 are conductively connected to the pipe 10 and the resonator 14, respectively. In accordance with ordinary practice and as an additional measure to minimize reflected waves, the characteristic impedances of the lines 25, 26 and 29, 30 are matched to the characteristic impedance of the respective wave guides to which the lines are connected.

Broken lines parallel to the central axis of the device indicate the approximate limits of the electron beam path 33 extending from the face 12 of the cathode to the inner wall of the resonator 14 through the aligned central apertures in the plates 11, 12 and 13, the constricted wave guide 15 and the aperture in the resonator. Electrons may be drawn from the cathode face 12 by virtue of the potential difference between the cathode and the anode structure comprising the metal parts exclusive of the cathode and heater. Suitable provision may be made for focusing the beam in order to constrain the greater portion of the electrons to remain within the limits of the path 33, such means being well known in the art and comprising, for example, a focusing coil 18 and a battery 16 for maintaining a strong, steady magnetic field in the direction of the path 33.

In the operation of the device of Fig. 1, the speed of the electrons along the direction of the path 33 may be adjusted to be substantially equal to the speed of propagation of electromagnetic waves along the same path. The baffle plates 11 are useful in bringing about a substantial equality of speeds, the plates producing a structure in the nature of an inductively loaded line, the speed of propagation along which may be reduced to a fraction of the speed of propagation of electromagnetic waves in free space. It is known that the waves in free space travel with substantially the speed of light and that electrons in electron beams produced by means of reasonably convenient voltages are of the order of magnitude of one-tenth the speed of light and less, according to the voltage. By suitable design of the wave guide 10 and plates 11 the speed of propagation of waves along the path 33 may be

brought within easy reach of the adjustment of electron speed available by varying the potential of the battery 22. The resistance value of the resistor 24 is adjusted to be as nearly as possible an exact impedance match for the loaded transmission line structure comprising the wave guide 10 and the plates 11. Electromagnetic waves impressed upon the input coaxial line 25, 26 are propagated through the wave guide 10 and absorbed in the resistor 24. The object of this arrangement is to provide a pure traveling wave in the wave guide 10 with no appreciable reflection of the wave from the end plate 13. Wave reflections from the end plate 12 are minimized by the impedance matching at the junction with the line 25, 26. The traveling waves progressing from left to right through the wave guide 10 react upon the electrons from the cathode face 12 and, by virtue of the equality of speeds, the electrons progress along the wave guide keeping substantially abreast of the electromagnetic waves. Electrons which enter the region of the wave in the proper phase to absorb energy from the wave are continuously accelerated by the wave and other electrons entering in the proper phase to deliver energy to the wave are decelerated. As long as the changes of speed of the electrons remain small in comparison with the initial electron speed produced by the potential of the battery 22, the electrons which are speeded up continue to be so affected throughout the length of the guide 10 and the electrons which are slowed down likewise are so affected continuously throughout their transit of the guide. Electron bunching occurs due to the fact that the accelerated electrons tend to overtake those which are decelerated. The result is that the electron stream upon entering the constricted section 15 is characterized by electron density variations. In other words there is a tendency for the electrons to become grouped in bunches separated by spaces containing relatively few electrons. Further bunching of the electrons may occur during their passage through the section 15. Upon entering the interior of the resonator 14, the bunches of electrons induce alternating electric currents in the inner surfaces of the resonator in well-known manner. In other words, the electrons excite the resonator into oscillation. An output of oscillations in the form of an electromagnetic wave is impressed upon the output coaxial line 29, 30 by means of the coupling loop 31. The impressed wave upon the input coaxial line 25, 26 is not transmitted to the output coaxial line 29, 30 but is absorbed in the resistor 24, or is suppressed in the intermediate wave guide section 15, which may be of such small diameter that it will not freely propagate electromagnetic waves of the frequency or frequencies impressed upon the input line.

The device of Fig. 2 is similar to that of Fig. 1 except that the resonator 14 is replaced by a section of loaded transmission line 48 with baffle plates 41 similar to the wave guide 10 and plates 11, respectively. The electron path passes through the central apertures and the constricted intermediate section 15 substantially as in Fig. 1. The wave guide 48 has terminating end plates 42 and 43, respectively, and a resistor 44 is connected between the end plate 42 and the next plate 41. The output coaxial line 29, 30 has its inner conductor connected to the end plate 43.

The operation of the device of Fig. 2 is similar to that of the device of Fig. 1. The elec-

beam stream is launched in the input wave guide 12 and in the constricted intermediate section 14 and the electron bunches induce alternating currents in the baffle plates and inner surfaces of the wave guides 16. The electron bunches keep substantially abreast of the electromagnetic waves in the wave guide 16 by virtue of equality of speeds, similarly as in the input wave guide 12. A pure traveling wave in the wave guide 16 is assured by the presence of a resistor 20 which sets as an impedance matching termination at the left-hand end of the wave guide 16 and the presence of the line 22, 24 which acts as an impedance matching termination at the right-hand end of the guide 16. The electron bunches give up energy to the electromagnetic wave in the wave guide 16 continuously along the length of the guide as long as they are not slowed down so much as to fall seriously out of phase.

Each of the wave guides 12 and 16 may be considered as an array of coupled resonators arranged in a tandem relationship, the coupling between adjacent resonators being provided by the centrally located aperture in the baffle plate 11 or 15. Additional coupling between the adjacent resonators may be provided by means of eccentrically located apertures 13 as shown in Figs. 3 and 4, the apertures 13 being in addition to the central apertures 11. In order to achieve a good modulation coefficient in the velocity varying or bunching of the electron beam, the diameter of the centrally located apertures 11 should be not much larger than the beam diameter. The size of the additional coupling apertures 13 can be adjusted to give the desired speed of propagation through the loaded wave guide.

The loaded wave guide structure may comprise a hollow cylinder with internal transverse baffle plates as shown in Figs. 1 and 2, or an alternative structure may be employed as illustrated in Figs. 3, 4 and 5. The hollow pipe wave guide with internal baffles is built up of a stack of the apertured plates or discs of Fig. 4 alternating with rings 31 as in Fig. 5, the plates or elements being united into a solid vacuum tight unit by soldering, welding or other suitable means.

Notwithstanding that the spaces between the plates 11 and 15 may be regarded as, and in fact are, cavity resonators, it will be noted that an array of such resonators, when suitably coupled, is essentially a band filter, and may have as broad a band as desired. No narrow band, or loosely coupled resonant devices are needed for the proper functioning of any portion of the devices disclosed.

If the speed of the electrons exactly equals the speed of propagation of the wave, it may be shown that the energy passing from the electron beam to the wave from the electrons which are slowed down is on the whole just equal to the energy passing from the wave to the beam and received by the electrons which are speeded up. It will be evident that this energy balance may be disturbed, as for example by maintaining the electron beam speed slightly greater than the speed of propagation of the wave in which case a net energy transfer will occur in the direction from the electron beam to the electromagnetic wave. This effect may be utilized in the input section of the devices illustrated to increase the effect of electron bunching. In the output section, the inductive effect of the electron bunches upon the wave guide

may be increased by employing an electron speed slightly greater than the speed of wave propagation in the guide.

It will be evident that the electron beam functions as an assemblage of moving electrically charged particles and that other particles, for example positive ions, might be substituted for the electrons.

What is claimed is:

1. An electron beam translating device comprising a hollow pipe wave guide, a plurality of regularly spaced parallel transverse baffle plates therein, each of said plates having two apertures of which one is centrally located and the other is eccentrically located, said eccentrically located apertures being substantially identical in shape and position and said centrally located apertures being aligned and substantially identical in shape and size, an electron beam source, means in said device for directing an electron beam from said source along a path passing through said centrally located apertures, and an impedance matching resistor contained between two of said baffle plates at one end of said wave guide, the terminals of said resistor being connected to the respective adjacent plates.

2. A broad band wave amplifier device comprising a hollow pipe wave guide, a plurality of baffle plates therein, each of said plates having a central aperture and a non-central aperture, an electron beam source, and means for projecting a beam from said source through the respective central apertures of said baffle plates, said non-central apertures providing coupling between spaces on opposite sides of a baffle plate.

3. A broad band wave amplifier device comprising a circular hollow pipe wave guide, a plurality of substantially identical parallel transverse baffle plates therein, each of said plates having a central aperture and an eccentric aperture, an electron beam source, and means for projecting a beam from said source through the respective central apertures of said baffle plates, said eccentric apertures providing coupling between spaces on opposite sides of a baffle plate.

4. A broad band electrical wave amplifier comprising an evacuated enclosure having means including a cathode and an anode for producing a beam of electrons, broad band wave guide means extending lengthwise along the path of said beam in energy transfer relation thereto having an initial portion nearest the cathode for modulating said beam in accordance with traveling waves in said initial portion, and having a final portion more remote from said cathode for extracting energy from the beam so modulated, means coupled to the said initial wave guide portion to impress waves of a band of frequencies to be amplified on said initial wave guide portion at the end thereof that is nearest the cathode, and an output circuit connected to said final wave guide portion at the end thereof that is most remote from the cathode, said wave guide means having the component of wave velocity parallel to said beam substantially equal to the velocity of electron travel of said beam, each of said wave guide portions at each of its ends being terminated in an impedance equal to the characteristic impedance of the respective wave guide portion.

5. A broad band electrical amplifier comprising means including a cathode and an anode for producing a beam of charged particles, a broad band-pass filter structure in the form of a wave guide extending lengthwise along the path

7
-said beam in energy transfer relation thereto, having an initial portion nearest the cathode for modulating said beam in accordance with traveling waves in said initial portion, and having a final portion more remote from said cathode for abstracting energy from the beam so modulated, means coupled to the said initial filter portion to impress waves of a band of frequencies to be amplified on said initial filter portion at the end thereof that is nearest the cathode, said wave impressing means being matched to said filter structure in impedance over substantially the whole of said frequency band and an output circuit for amplified waves connected to said final filter portion at the end thereof that is most remote from the cathode, said output circuit being matched to said filter structure over substantially the whole of said frequency band, the initial filter portion working into a succeeding filter portion, said portions being matched as to impedance looking in the direction away from the cathode, and the final filter portion working out of a preceding portion, said final portion and said preceding portion being matched as to impedance looking in the direction toward the cathode.

8. A broad band electrical amplifier comprising a source of charged particles, projecting means for forming particles from said source into a beam, a band-pass filter structure of elongated form extending lengthwise along the path of the projected beam in energy transfer relation thereto, said filter having an initial portion nearest the projecting means for modulating said beam in accordance with traveling waves in said initial portion, and having a final portion more remote from said projecting means in which waves may be induced by the beam so modulated, means coupled to the said initial filter portion to impress waves of the band of frequencies to be amplified upon said initial filter portion at the end thereof that is nearest the projecting means, said wave impressing means having its impedance substantially equal to the characteristic impedance of the filter over substantially the whole of the frequency pass band of the filter and a load circuit for induced waves connected to said final filter portion at the end thereof most remote from said projecting means, said load circuit having its impedance substantially equal to the characteristic impedance of the filter over substantially the whole of the pass band, the initial filter portion facing a matched termination in the filter structure looking away from the projection means and the final filter portion facing a matched termination in the filter structure looking toward the projecting means.

9. An electron beam translating device comprising an electron beam source, beam projecting means, a first wave guide means capable of broad band wave transmission when terminated at both ends in matching impedances, said first wave guide means extending lengthwise along the path of the projected beam in the portion of said path nearest the said beam projecting means in energy transfer relation to the beam for bunching electrons of the projected beam, matching impedance terminations at both ends of said first wave guide means, a second wave guide means capable of broad band wave transmission when terminated at both ends in matching impedances, said second wave guide means extending lengthwise along the path of the beam in the portion thereof more remote from the beam projecting means in energy transfer relation to the beam for absorb-

ing energy from the electrons of the beam, and matching impedance terminations at both ends of said second wave guide means, whereby the broad band capabilities of both said wave guide means are substantially realized.

10 5. An electron beam translating device comprising an electron beam source, beam projecting means, a first repetitive band pass filter structure forming a wave guide extending lengthwise along the path of the projected beam for a distance equal to several wavelengths of a wave to be transmitted, said wave guide being located adjacent the portion of the beam path nearest the said beam projecting means, whereby electrons are caused to become bunched in said beam, impedance terminations matched to said first wave guide connected thereto at both ends thereof, a second repetitive band-pass filter structure forming a wave guide extending lengthwise along the path of the projected beam for a distance of several wavelengths in a portion of the beam path more remote from said beam projecting means than said first wave guide for a distance of several wavelengths in energy transfer relation with the beam, whereby the beam induces a wave in said second wave guide, and impedance terminations matched to said second wave guide connected thereto at both ends thereof.

15 30 6. A broad band electrical amplifier comprising a hollow pipe wave guide, a plurality of transverse baffle plates therein, each of said baffle plates having an aperture, means including a cathode and an anode for producing a beam of charged particles directed along a path extending lengthwise along said wave guide and passing through the said apertures in said baffle plates, means coupled to the said wave guide to impress waves of a band of frequencies to be amplified on said wave guide at the end thereof that is nearest the cathode, said wave impressing means being matched to said wave guide and apertured baffle plate structure in impedance over substantially the whole of said frequency band and an output circuit for amplified waves connected to said structure at the end thereof that is most remote from the cathode, said output circuit being matched to said structure over substantially the whole of said frequency band.

15 45 40 7. A broad band electrical amplifier comprising a source of charged particles, projecting means for forming particles from said source into a beam, a band-pass filter structure of elongated form extending lengthwise along the path of the projected beam in energy transfer relation thereto, said filter comprising a hollow pipe wave guide having a plurality of spaced transverse baffle plates therein, each of said baffle plates having an aperture, which apertures are aligned, and the filter being mounted in position to accommodate said beam of charged particles within in said aligned apertures, said filter having an initial portion nearest the projecting means for modulating said beam in accordance with traveling waves in said initial portion, and having a final portion more remote from said projecting means in which waves may be induced by the beam so modulated, means coupled to the said initial filter portion to impress waves of the band of frequencies to be amplified upon said initial filter portion at the end thereof that is nearest the projecting means, said wave impressing means having its impedance substantially equal to the characteristic impedance of the filter over substantially the whole of the frequency band of

The filter and a load circuit for induced waves connected to said final filter portion at the end thereof most remote from said projecting means, said load circuit having its impedance substantially equal to the characteristic impedance of the filter over substantially the whole of the pass band.

11. An electron beam translating device comprising an electron beam source, beam projecting means, a first wave guide means capable of broad band wave transmission when terminated at both ends in matching impedances, said first wave guide means comprising a hollow pipe wave guide having a plurality of spaced transverse baffle plates therein, each of said baffle plates having an aperture, which apertures are aligned, and the said wave guide being mounted in position to accommodate within said aligned apertures the beam from said beam projecting means, said first wave guide means extending lengthwise along the path of the projected beam in the portion of said path nearest the said beam projecting means in energy transfer relation to the beam for bunching electrons of the projected beam, matching impedance terminations at both ends of said first wave guide means, a second wave guide means of similar construction and properties to said first wave guide means extending lengthwise along the path of the beam in the portion thereof more remote from the beam projecting means in energy transfer relation to the beam for absorbing energy from the electrons of the beam, and matching impedance terminations at both ends of said second wave guide means, whereby the broad band capabilities of both said wave guide means are substantially realized.

12. An electron beam translating device comprising an electron beam source, means for projecting a beam of electrons from said source along a given path, a first repetitive band pass filter structure forming a wave guide extending

lengthwise along the path of the projected beam for a distance equal to several wavelengths of a wave to be transmitted, said filter structure comprising a hollow pipe wave guide having a plurality of spaced transverse baffle plates therein, each of said baffle plates having an aperture, which apertures are aligned, said filter structure being mounted in position to accommodate said beam within the aligned apertures, said wave guide being located adjacent the portion of the beam path nearest the said beam projecting means, whereby the electrons are caused to become bunched in said beam, impedance terminations matched to said first wave guide connected thereto at both ends thereof, a second, substantially identical, repetitive band-pass filter structure forming a wave guide extending lengthwise along the path of the projected beam for a distance of several wavelengths in a portion of the beam path more remote from said beam projecting means than said first wave guide for a distance of several wavelengths in energy transfer relation with the beam, whereby the beam induces a wave in said second wave guide, and impedance terminations matched to said second wave guide connected thereto at both ends thereof.
